UNITED STATES PATENT OFFICE.

VAN SUMERLIN, OF PINETOPS, NORTH CAROLINA.

TOY.

No. 874,878.

Specification of Letters Patent.

Patented Dec. 24, 1907.

Application filed March 13, 1907. Serial No. 362,180.

To all whom it may concern:

Be it known that I, VAN SUMERLIN, citizen of the United States, residing at Pinetops, in the county of Edgecombe and State of North Carolina, have invented certain new and useful Improvements in Toys, of which the following is a specification.

The present invention provides a unique toy of the variety adapted to simulate the feats of acrobats upon trapeze or horizontal bar and comprising a suitable frame-work and a jointed figure, the latter being supported by spaced strands having a twist imparted thereto and which control the movements of the figure upon application of pressure to movable parts of the frame-work.

For a full understanding of the invention, reference is to be had to the following description and accompanying drawings.

While the invention may be adapted to different forms and conditions by changes in the structure and minor details without departing from the spirit or essential features thereof, still the preferred embodiment is shown in the accompanying drawing which is a perspective view of a toy embodying the invention.

The frame-work comprises spaced pressure bars supported by means of a strut 2, said pressure bars being provided near their upper ends and in opposite sides with grooves or notches 3 in which are fitted strands 4. The strands preferably consist of portions of a cord which is doubled upon itself and secured, the end portions of the cord being seated in the notches or grooves 3 of the pressure bars. A jointed figure 5 is mounted upon the strands 4, the latter passing through spaced openings in members of the figure so

that upon subjecting the strands to tension after first giving a twist thereto, motion will be imparted to the figure by the tendency of the strands to untwist or straighten, the parts being so arranged that the figure will normally hang pendent and impart a twist to the strands 4 when the latter are relaxed.

Supporting bars 6 are arranged in parallel relation and are connected to the upper ends of the pressure bars 1 and are preferably arranged exterior to said bars, thereby relieving the fastenings 7 of strain when the toy is in operation. The supporting bars 6 are pivotally connected to the pressure bars at a middle point, thereby equalizing the weight and strain upon the frame-work. By having the supporting bars 6 pivoted to the pres-

sure bars, they may be turned to admit of folding the toy into compact form or to change the relative inclination of the supporting bars to the pressure bars to obtain any desired effect. Under cut notches 8 are provided in a side of the supporting bars to receive the strands and in the event of said supporting bars receiving a figure near each end only, notches 9 are formed in the extremities of the supporting bars to receive the companion strands coöoperating with the strands fitted in the under cut notches or grooves 8.

The jointed figures 5 may be of any construction and design to represent either animals or the human form according to the nature of the toy as a whole. The figures may be artistically finished or have any grotesque or ludicrous appearance so as to add to the amusement created by the various antics and comical positions assumed in manipulating the toy by applying pressure to the lower ends of the bars 1 in the manner well understood. The toy is operated by gripping the lower end of the pressure bars 1 in the hand and upon closing the hand the lower ends of the pressure bars are drawn together and the upper ends separated, thereby subjecting the series of strands 4 to linear tension with the result that they tend to untwist or straighten and thereby cause the figures to assume an elevated position. By gripping and suddenly relaxing the lower ends of the pressure bars, the figures receive a quick impulse thereby causing them to assume various positions which either appeal to the aesthetic or ludicrous according to the design of the figures themselves.

It is to be understood that in arranging the parts, the strands receive a quarter twist when the figures hang pendent which is their normal position, so that tension applied to the strands 4 by manipulating the pressure bars tends to straighten said strands and to actuate the figures by causing them to rise, said movements being varied and controlled by deftly manipulating the pressure bars by quickly contracting and releasing the muscles of the hand.

Having thus described the invention, what is claimed as new is:

1. A toy comprising spaced pressure bars, supporting bars connected intermediate of their ends to said pressure bars, spaced strands attached to said supporting bars upon opposite sides of the pressure bars, and

toy figures mounted upon said strands, the strands of the several pairs being twisted and adapted to impart motion to the figures supported thereby when subjected to linear tension.

2. A toy comprising spaced pressure bars, supporting bars pivotally connected midway of their ends to said pressure bars and adapted to be turned to any relative angular position, toy figures and twisted strands connecting said toy figures to said supporting bars.

3. In a toy the combination of spaced pressure bars, supporting bars having connection

with said pressure bars and having under cut notches or grooves, companion strands fitted in said undercut grooves and being twisted and jointed figures mounted upon said strand and having motion imparted thereto by the tendency of said strands to straighten when subjected to linear tension.

In testimony whereof I affix my signature in presence of two witnesses.

VAN SUMERLIN. [L. s.]
